REST STRUCTURE WITH ADJUSTABLE BACK

Maurice Glick, Brooklyn, and Norman Nicholas,
Binghamton, N. Y.

Application September 2, 1949, Serial No. 113,712

3 Claims. (Cl. 155—163)

1

This invention relates to chair, bed, couch or similar seat or rest structures with an adjustable back and concerns more particularly the mechanism for operating the back to and from adjusted positions.

It is an object of the present invention to provide a chair or similar structure of the aforesaid type having a back wherein the adjustment of said back can be effected from a location of one of the arms of the chair and wherein said back will be held in adjusted position until forcedly and automatically returned to an elevated or end position.

It is another object of the present invention to provide a mechanism capable of adjusting the back of the chair in any desired position relatively to the seat of the chair without the need of a rack bar or other complicated devices which generally permit only a limited number of positions for adjusting the back of the chair or the like.

It is another object of the present invention to provide means affording an effective and reliable construction of a mechanism for moving the back of the chair to adjusted position, for retaining the back in said adjusted position, and finally for returning said back to initial or any other adjusted position.

Other objects of the present invention are to provide a chair, couch, bed or the like, with an adjustable back, which is of simple construction, has a minimum number of operable parts, is inexpensive to manufacture, easy to operate, may readily be built in the sides of the structure, requires only little space for accommodation within the sides of the chair or structure, is convenient to use and efficient in operation.

For other objects and for a better understanding of the invention, reference may now be had to the following detailed description taken in connection with the accompanying drawings, in which:

Fig. 1 is a side-elevational view of an arm chair with upholstered side portion thereof removed to expose the frame and to illustrate the mechanism embodying the invention.

Fig. 2 is a side-elevational view of the opposite side of the chair of Fig. 1.

Fig. 3 is an enlarged perspective view of the mechanism embodying the invention and shaped for application to a chair.

Fig. 4 is an enlarged fragmentary and sectional view of the mechanism, taken along line 4—4 of Fig. 3.

Fig. 5 is a sectional view taken along line 5—5 of Fig. 4; and

2

Fig. 6 is a fragmentary perspective view of a part of the spreading device forming part of the mechanism of Fig. 3 and shown in a different position than that seen in Fig. 3.

Referring now to the drawings, there is disclosed an armchair A having rearward and upwardly extending spaced supporting members 10, 11. These members may be curved at their upper ends and are provided with notches 12 in the rear edges of said members. Forwardly from these supporting members 10, 11 extend, respectively, side frame members 13 and 14 which terminate, respectively, at arm supports 15 and 16 which extend to horizontal arm resting portions 17 and 18. A cushion 19 forms the seat of the chair and may extend forwardly beyond the arm supports 15 and 16. A forward upholstered structure 21 is provided to support the cushion seat 19. The rear ends of the arm rest portions 17 and 18 are connected to the upper parts of the curved supporting members 10 and 11.

Between the supporting members 10 and 11, there is positioned and swingably supported an adjustable back 22. This adjustable back can be constructed in the ordinary manner and is cushioned to provide comfort for the person reclining in the chair.

To opposed sides of the back 22 there are, respectively, connected angle arm members 23 and 24. The angle arm member 23 is connected by a pivot pin 25 to an upright bar 26 rigidly fixed to the vertical support 10 and extending across the end of notch 12 thereof.

This bar or plate 26 is fixed to the support 10 by any suitable means, such as screws 27. Plate 26 has an offset median portion 28 providing stops 29 and 31 for limiting the upward and downward movements of the back 22 and determining the extreme positions of the latter. The angle arm 23 is pivoted on pin 25 passing through offset portion 28. The side edges of angle arm 23 will abut against the stops 29 and 31 as the back is raised or lowered to end positions. The arm 23 is inwardly offset at 23a so as to extend laterally and inwardly through the notch 12 for engagement with and fixation to the side frame of the back 22.

On the opposite side frame of back 22, there is a similar swinging mechanism attached which, however, is devoid of any adjusting device and more or less serves to guide back 22 during its movements and to afford a stabilization of the back structure.

Angle arm 24 is connected to said opposite side frame of the back 22 and is pivoted at 35 to vertically extending plate 33 having the median offset portion 34. The forwardly extending end

of the arm 24 carries a tension spring 36 which acts upon the arm 24 to urge back 22 to its elevated or one of its extreme positions. The other end of the tension spring 36 is anchored on a bracket 37 fixed to the base of the chair A. A similar tension spring 38 is connected to the angle arm 23 as indicated at 39 (Fig. 1) and acts upon the back 22 in conjunction with the tension spring 36 to automatically urge the back 22 to elevated position as soon as the mechanism is released, to which reference is made further below. Tension spring 38 is anchored on a bracket 41 located at the base of the chair A.

Connected to the support 10 and to the side frame member 13 is a horizontally extending strap 42 to which is connected by means of a pivot pin 43, a U-shaped member 44, having vertically spaced horizontally extending flap or flange portions 45 and 46 with openings therein through which extend a round rod 47. This round rod is pivotally connected at 48 through the forward end of the angle arm 23.

Spaced inwardly from the horizontally extending portions 45 and 46 of the U-shaped member 44 are respectively openings 51 and 52 adapted to respectively accommodate tongue portions 53 and 54 of edge gripping elements 55 and 56. These edge gripping elements are respectively provided with openings for receiving the rod 47, and these openings are of larger diameter than the diameter of the rod 47 so as to permit the angular movement of the gripping elements in order that the edges of the openings can respectively engage the sides of the rod to grip the rod and prevent the movement of the rod through the gripping elements and the U-shaped member 44 whereby to retain the back 22 in its adjusted position. The gripping elements 55 and 56 are respectively urged into edge gripping engagement with the rod 47 by springs 57 and 58 reacting respectively against the horizontally extending portions 45 and 46 of the U-shaped member 44. The openings in the gripping elements 55 and 56 are indicated, respectively, at 59. The rod 47 has a cotter pin at its free end as indicated at 61 to prevent the disengagement of the rod 47 from the U-shaped member 44.

The gripping elements 55 and 56 are spread against the action of their springs by horizontally extending spreading lever members 62 and 63, having inwardly bent ends engaging with the free ends of the gripping elements. These spreading elements 62 and 63 are pivoted to each other and to an outwardly offset end 64 of the strap 42 by a pivot pin 65. A vertically extending strap 66 is connected to the horizontally extending strap 42 adjacent the offset end 64 thereof by a pin 67 and will serve to support that end of the strap 42. The lower end of the vertical support strap 66 is connected by a pin 68 to the base of the chair.

The forward end of the spreading member 63 is bent as indicated at 69 and receives the plate 71, which is pivotally connected by a pin 72 to the forward end of the spreading member 62. The plate 71 has a notch 73 for receiving the bent portion 69 of the spreading member 63. The plate 71 can accordingly be pivoted on the end of the spreading member 63 to cause the separation of the ends of the spreading members 62 and 63 and the release of the gripping elements 55 and 56 upon the rod 47. This action is effected when the plate 71 assumes the position shown in Fig. 6.

The plate 71 is worked by a rod 74 connected at

its lower end to the plate 71 and at its upper end the rod 74 is connected to a bell crank 75 pivoted as indicated at 76 upon a bracket 77. This bracket has an operating rod 78 slidable therethrough with a knob 79 thereon. This rod is connected to the bell crank lever 75 and when depressed, the spreading elements are pivoted by the working of the plate 71 and the rod 47 is released to free the back 22 of the chair.

In operation it will be seen that the back 22 when released can be adjusted in a rearwardly extended position by pushing backwardly upon the button or knob 79 being depressed to release the gripping elements 55 and 56. As soon as the desired position of the back has been obtained, the button is released and the rod 47 is gripped to hold the back in the exact position to which it has been adjusted. The back can be adjusted to a horizontal position if desired, as shown in Fig. 1, or it can be held rigid at any location between the raised position and the horizontal position. The rod 47 can be gripped at any location upon the same, and accordingly there are any number of positions to which the back can be set. The device does not depend upon rack teeth, so that the number of positions to which the back can be adjusted are unlimited. Accordingly, there has been provided a retaining mechanism for a chair back which is not dependent upon rack teeth.

While various changes may be made in the detailed construction, it shall be understood that such changes shall be within the spirit and scope of the present invention as defined by the appended claims.

What is claimed is:

1. In a chair or similar article; a substantially vertical supporting structure, a seat portion supported upon said supporting structure, a back adjustably connected to said supporting structure in rear of the seat portion, arms connected to the opposite sides of the back, means for pivotally connecting said arms to said supporting structure, spring means connected to said arms urging the back to its elevated position, a slide rod extending from one of said arms and being pivotally connected thereto, means for gripping said rod to retain the back in its adjusted position, and means accessible to the user of the chair for releasing said gripping means, said gripping means including elements adapted to be spread apart to release the rod, said means for releasing said gripping means comprising spread elements pivotally connected to each other and to said supporting structure, a plate pivotally connected between the outer ends of said spread elements to separate the same, and a hand operating device connected to the plate to effect its actuation whereby said spread elements will be spread from one another and the grip elements will be released from the rod.

2. In a chair or similar article; a supporting structure including a seat portion thereon, a swingable back adjustably connected to said supporting structure to assume elevated and obliquely adjusted positions, respectively, arms connected to the opposite sides of the back, means pivotally connecting said arms to said supporting structure, spring means connected to said arms urging the back to its elevated position, a slide rod extending from one of said arms and pivotally connected thereto, means for gripping said rod to retain the back in its adjusted position, releasable means accessible to the user of the chair for operating said gripping means, said

gripping means comprising a U-shaped member having flange portions with openings in alignment with each other, said rod being slideable through said openings of said flange portions, gripping elements having respective openings normally permitting passage of said rod therethrough and, respectively, movable with respect to said U-shaped member, springs about the rod normally urging said gripping elements at their openings into engagement with the rod, said releasable means for the gripping means including spread elements pivotally connected to said supporting structure and to one another and having inwardly bent ends engaging with the free ends of the gripping elements, one of the spread elements being longer than the other, an operating member connected between the operating ends of the spreading elements to effect the separation of one another, and a hand operated device including a rod connected to said operating member to actuate the same, said hand operating device being secured to said supporting structure.

3. In a chair frame and like piece of furniture having a swingable back; means connected to said back, said means including an arm pivotally supported on said chair frame, a rod element operatively connected to said arm, a substantially U-shaped member having flange portions provided with openings, two gripping elements movably arranged on said U-shaped member and provided with openings defined by edges, said openings of said flange portions and said openings of said gripping elements being registerable with one another and being shaped for the passage of said rod element therethrough, spring means surrounding said rod element at locations

between said flange portions and said gripping elements and normally urging the latter against each other and to thereby provide edge-gripping engagement with said rod element, spreading lever means disposed to extend between said gripping elements and to spread the latter apart for achieving registry of said openings of said flange portions and of said openings of said gripping elements whereby said rod element may pass therethrough for adjusting purposes, and push button means remote from said U-shaped member and linked to said lever means to thereby operate said gripping elements against said spring means and in relation to said rod for adjusting 15 said back.
